UNITED STATES PATENT OFFICE.

WILLIAM L. MERSFELDER, OF KENNEDY HEIGHTS, OHIO, ASSIGNOR TO THE STAR FOUNDRY COMPANY, OF COVINGTON, KENTUCKY, A CORPORATION OF KENTUCKY.

DESIGN FOR A STOVE.

47,962.

Specification for Design.

Patented Oct. 12, 1915.

Application filed April 27, 1915. Serial No. 24,358. Term of patent 14 years.

To all whom it may concern:

Be it known that I, WILLIAM L. MERSFELDER, a citizen of the United States, residing at Kennedy Heights, in the county of Hamilton and State of Ohio, have invented a new, original, and ornamental Design for Stoves, of which the following is a specification, reference being had to the accompanying drawing, forming part thereof.

In the drawing, Figure 1 is a front elevation of my stove, showing my new design.

Fig. 2 is a side elevation thereof. Fig. 3 is a detail of one of the scroll decorations thereon.

I claim:

The ornamental design for a stove, as shown.

WILLIAM L. MERSFELDER.
